UNITED STATES PATENT OFFICE.

ORIN MARTIN, OF BLOOMFIELD, IOWA.

IMPROVEMENT IN SAW-SHARPENERS.

Specification forming part of Letters Patent No. 175,837, dated April 11, 1876; application filed November 17, 1875.

To all whom it may concern:

Be it known that I, ORIN MARTIN, of Bloomfield, in the county of Davis and State of Iowa, have invented a Saw-Filing and Setting Machine, of which the following is a specification:

The object of my invention is to furnish a portable machine, by means of which a straight file can be automatically operated to move vertically and laterally in a manner similar to the movements required in filing a saw by hand; and that will also at the same time set the teeth by the automatic stroke of a hammer and a punch upon an adjustable anvil. It consists in an adjustable sliding file-holder, an adjustable suspended frame carrying the file-holder and driving mechanism, a sliding saw-carrier, and a hammer and anvil being formed, mounted, and combined, upon a portable frame, as hereinafter fully set forth.

Figure 1 of my drawing is a perspective view; giving a general idea of the construction and operation of my invention.

A is the base of the frame upon which my machinery is mounted. It may be wood or metal, and vary in dimensions to suit machines of different sizes. B B are the corner posts on the front side of the frame. C is one of the rear corner posts. D is the driving-wheel journaled to the end of the shaft a, which shaft has its bearing in the frame midway between the posts B. E is a pinion actuated by the driving-wheel D. It is rigidly fixed on the end of the shaft b, which shaft has its bearings in the suspended auxiliary frame that carries the file-holder. c d are corner posts representing the auxiliary, adjustable, suspended frame. F is a rock-shaft, operated by an arm extending therefrom to a cam or pin on the driving-wheel, to work the setting device. f f are parallel rails rigidly fixed upon the frame B C to support the sliding saw-carrier G. H represents a saw clamped upon the top of the carrier G. J is the hammer which strikes the punch or setter upon the saw-teeth and anvil. g is a crank-wheel rigidly fixed on the end of the shaft b, opposite the pinion E, to impart a vertical reciprocating motion to the file-holder and file. K is a rack rigidly fixed to the posts B. It is concentric with the axle a that supports the suspended

frame c d, and serves as a means of holding that adjustable frame at various angles. A latch or set-screw carried by the suspended frame engages the rack K and locks the frame to the rack. h is the top handle of the file-holder. It can be adjusted in a collar to hold the different edges of the file to the saw.

Fig. 2 is a transverse sectional view, giving details of construction and illustrating the means employed to impart both vertical and lateral motion to the file-holder and file.

The driving-wheel D on the shaft a actuates the pinion E on the shaft b. The crank-wheel g, on the opposite end of the shaft b, is connected with the file-holder m by a pitman, n. The file-holder m slides vertically in suitable bearings fixed in or on the post d of the suspended frame. L is an adjustable cam-wheel rigidly secured on the shaft b by a set-screw, to impart a lateral motion to the file. p is a lever, bifurcated at its lower end, to engage the cam-wheel L. It is pivoted near its longitudinal center to a bearer extending from the posts c. At its top it is linked or hinged to an adjustable collar, r, that is rigidly secured to the shaft a by a set-screw. The extent of the lateral motion of the file can be regulated as required for different saws by adjusting the cam-wheel L and collar r on their respective shafts b and a. Each revolution of the cam L moves the entire suspended frame c d, file-holder, and file to and from the saw simultaneously with the action of the crank-wheel g, which imparts a reciprocating vertical motion to the file-holder and file. An automatic movement is thus given to the file very similar to the motions required in filing a saw by hand.

Fig. 3 is a longitudinal sectional view, illustrating the construction, application, and operation of my setting device.

s is an adjustable anvil secured in any suitable manner, contiguous to the inside rail f, in such a position that the saw-teeth will extend over it as the saw is moved with the carrier G. t is a punch or setter suspended in a suitable frame over the anvil s. u is a crank or adjustable arm projecting from the rock-shaft F. v is a prop linked or pivoted to the end of the arm u, and reaches up to the helve of the hammer J to lift the hammer.

A suitable spring connected with the hammer forces the hammer down to strike the setter *t* when the prop *v* is withdrawn. *w* is a weighted pawl connected with the saw-carrier *G* in such a manner as to perform the functions of a ratchet in moving forward the sliding saw-carrier *G*. *x* is a pitman connecting the pawl *w* with an arm *y* projecting from the end of the rock-shaft *F* in such a manner that it can be adjusted to govern the movement of the saw as required for the operation of the file. When the arm *e* projecting from the opposite end of the shaft *F* is engaged by the pin projecting from the driving-wheel *D*, the shaft *F* is rocked thereby and the prop *v* pushed upward to lift the hammer *J*, and the pitman *x* is simultaneously pushed forward by the arm *y* to move the saw-carrier *G* by means of the gripping weighted pawl *w* on its front end.

From the descriptions and functions of the different parts set forth, it is obvious that a saw may be clamped upon the saw-carrier *G* and made to pass the anvil and file to have its teeth set and filed by simply turning the driving-wheel *D*, and that the suspended frame carrying the file may be readily adjusted to hold the file at any angle desired and as may be required for different forms of saw-teeth. Each revolution of the pinion *E* draws the file down over the saw and lifts it away and up again. The relative diameters of the pinion *E* and driving-wheel *D* may vary to determine the number of file-cuts or strokes to each revolution of the driving-wheel and each forward motion of the saw-carrier and

saw. When the saw has passed through the machine once it is turned in the carrier and passed through again to file and set the teeth completely.

I claim as my invention—

1. In a saw-filing machine, the shaft *a*, carrying the driving-wheel *D*, and the adjustable collar *r*, in combination with the suspended frame *c d*, carrying the shaft *b*, pinion *E*, cam-wheel *L*, pivoted lever *p*, and crank-wheel *g*, substantially as described, to impart vertical and also lateral motion to a file.
2. The combination of the sliding file-holder *h m*, the pitman *n*, crank-wheel *g* on the shaft *b*, and the suspended vibrating frame *c d*, substantially as and for the purposes specified.
3. The combination of the saw-carrier *G*, track-rails *f f*, adjustable anvil *s*, setter *t*, hammer *J*, rock-shaft *F*, carrying the prop *v* and arms *w* and *e*, and the driving-wheel *D*, having pins or cams to engage the arm *e*, substantially as described, to set the teeth of the saw.
4. The rock-shaft *F* having the adjustable arm *u*, carrying the prop *v*, in combination with the hammer *J*, substantially as and for the purposes shown and described.
5. The rock-shaft *F* having the arm *y*, in combination with the adjustable pitman *x*, weighted pawl *w*, and saw-carrier *G*, substantially as and for the purposes shown and described.

ORIN MARTIN.
